CLAIM

The ornamental design for a chocolate raspberry, as shown and described.

DESCRIPTION

FIG. 1 is a top front perspective view of our chocolate raspberry design.

FIG. 2 is an elevational view thereof, wherein the elevational view is identical from all sides.

FIG. 3 is a top plan view of FIG. 1.

FIG. 4 is a bottom plan view of FIG. 1.

FIG. 5 is a front elevational view of a segment of FIG. 1 shown separately for clarity of illustration.

FIG. 6 is a rear elevational view of FIG. 5; and,

FIG. 7 is a right side elevational view of FIG. 5.
